J. G. WALLMANN,
BRAKE,
APPLICATION FILED JAN. 10, 1917.

1,302,738.

Patented May 6, 1919.

UNITED STATES PATENT OFFICE.

JOHANN G. WALLMANN, OF OAKLAND, CALIFORNIA.

Brake.

1,302,738.

Specification of Letters Patent.

Patented May 6, 1919.

Application filed January 10, 1917. Serial No. 141,675.

To all whom it may concern:

Be it known that I, JOHANN G. WALLMANN, a citizen of the United States, residing at the city of Oakland, in the county of Alameda and State of California, have invented certain new and useful Improvements in Brakes, of which the following is a specification.

My invention relates to improvements in brakes.

The object of my invention is to provide a vacuum brake for automobiles operated from the vacuum of the intake manifold used in connection therewith which does not interfere with the service or emergency brakes on the automobile and which has novel means for allowing a vacuum to be drawn in a chamber of one of its cylinders, and which has other advantages which will hereinafter appear.

The accompanying drawing shows a sectional view of my apparatus, parts of which are shown in side elevation.

In the drawing 1 shows a suitable intake manifold to a gas-motor. A pipe 2 connects said manifold to valve port 31 and a branch pipe 3 connects said pipe 2 with valve port 77. A cylinder 4 has a piston or valve 5 therein and said valve has a transverse aperture 6 therethrough. The said valve or piston has a by-pass 7 extending vertically in its upper portion as shown. A cylinder cap 8 fits upon said cylinder, the said cap having an air vent 15 therethrough. A piston rod 73 is secured in said piston and has a cap 16 wherein is a seat for spring 9, which spring contacts at its lower end with said cap 8. A wire 17 is secured in said cap 16 and is partly inclosed by guide tubing 18. A steering post 25 having tubing 19 on bent wire 17 therein, the said wire being secured in push-button rod 21 by connection 20. The said push-button rod 21 has push-button 23 and also threads 22 in connection therewith. Steering wheel 24, shown broken away, is connected to steering post 25. A transverse wall in cylinder 4 has apertures or vents 14 therethrough. A cylinder cap 11 is fitted on the lower end of cylinder 4 and has a valve seat therein in which fits head 10 of the valve stem projecting upwardly therefrom. A spring 12 is on said valve stem and which engages said head and the wall above the same as shown. A spring chamber 30 is in said cylinder 4. A pipe 27 connects the passage way 28 of cylinder 4 with the forward

chamber 37 of cylinder 32, the said pipe 27 being secured in the opening of cap and bracket 38. A piston 34 is connected to piston rod 35. The piston rod 35 is slidable in the central opening of rear end cap and bracket 40. The upper opening of said cylinder 32 has a pipe 54 connecting the same with one of the side branches of cylinder 52 extending from by-pass 50 of piston 51. A pipe 26 connects a transverse opening in cylinder 4 with the opposite transverse opening in cylinder 52. A vent 49 in cylinder 52 opening into the piston chamber in said cylinder is shown. The stem or valve rod of said piston 51 has a slot 87 penetrated by centrally pivoted lever 79. Rod 80 is slid able in the slideway of the slide bar of bracket 81 secured to a cross-piece as shown, which cross-piece has an opening in which the stem 84 of the foot piece above the same is movable. A catch 83 secured to said cross-piece is engageable with the notch 86 of said stem 84, the said stem being pivoted at its lower end as shown. A spring 82 on rod 80 intervenes between stem 84 and the slide-bar of bracket 81. A piston 45 in the lower part of said cylinder 52 has a dog 44 projecting downwardly and engageable with the teeth of notched bar 43, which is connected by coupling 42 to rod 35 operable in stuffing-box 41. 46 designates the lower cylinder chamber of cylinder 52, a spring 47 being on the connecting piece projecting upwardly from piston 45 and slidable with piston 51. The piston 51 has a passage-way 48 as shown and a passage-way 55 connects one of the branches of cylinder 52 with the lower chamber of said cylinder. An air vent 75 leads downwardly from the cylinder 52 into the box 95. A rod 92 extends through a side opening in box 95 and connects notched bar 43 with a clevis 56 which is connected to threaded plug 57 screwed in cylinder 58 containing piston 61 and piston rod 59, which rod works in the slideway of head 60 upon said cylinder 58.

A clevis 62 connects piston rod 59 with arm 63 linked to arm 65 by the brake cross shaft 64. A spring 90 is connected to arm 65 and extends to a suitable place where the same is secured at its other end. A connecting rod 66 is pivoted to the outer end of arm 65, said connecting rod being pivoted to arm 67 connected to drum 68 and pivoted intervening spreader 70, which spreader is endwise engaged by the shoes of the ex-

pansible band 69 in said drum 68. The said band 69 is centrally pivoted to said drum 68.

My said brake is operated from the vacuum in the intake manifold. It does not 5 interfere with the service or emergency brakes on the car. The brake drop arm 63 is attached to the cross-shaft of either the emergency or the service brake. Piston cylinder 32 and its parts is fixed in the 10 frame of the car. The valve in cylinder 4 is set and the pipe connections are connected to said piston-cylinder and the intake manifold, and the manual push-button control on the steering post 25 is connected 15 to the valve for the operation when desired to be commenced.

By starting the gas-motor of the car and unlocking the push button at the thread 22 by giving it a couple of turns to the left 20 spring 9 forces the button 23 upwardly by means of the steel wire 17, thus simultaneously raising piston 5 in the cylinder 4 and which closes the aperture 31 and opens the aperture at 77. The valve in this position 25 releases the brake in the following manner:—A vacuum is drawn in the cylinder space marked 46 by means of the pipe 2, pipe 3, passage 6, pipe 26, and passage 55, causing the piston 45 to be raised in the 30 cylinder 52. The piston 45 raises the dog 44 out of the notched piece 43, simultaneously raising the piston valve part 51, passage way 48 allowing a vacuum to be drawn in the chamber 36 of the cylinder 32. This 35 partial vacuum in the chamber 36 causes the piston 34 and the connected parts 35, 43, 92, 56, 57, 58, 59, 60, 61, 62, 63, 65, 66 and 67 to be drawn backward, releasing the brake bands in the drum 68. In this position 40 the brakes are free. When you wish to put on the brakes as the car is moving the operator causes the clutch to be thrown out and pushes down on the button 23—this movement opening the port 31 and closing 45 the port 77 a partial vacuum is drawn from the chamber 37 of cylinder 32 which causes the piston 34 and the connected parts 35, 42, 92, 43, 56, 57, 58, 59, 60, 62, 63, 65, 66, and 67 to be drawn forwardly. This movement 50 causes the bands 69 to be spread in the drum 68, breaking the momentum of the car. This downward movement of the piston 5 of the piston valve mechanism simultaneously opens the passage way 7, 55 which allows air to enter the cylinder chamber 46, spring 47 forcing piston 45 downwardly allowing the dog 44 to catch in a notch of bar 43. This downward movement of the piston 45 carries the piston valve 60 part 51 downwardly so that the passage 50 allows air to enter the cylinder chamber 36. The foot piece 84 is intended to be used to throw out the dog 44 when the motor of the car has stopped running or it may be 65 used to keep the dog out of service. This

is done by pressing down on the foot piece 84 and at the same time pressing forwardly until the slot 86 catches on the catch 83, and such releasing mechanism is connected to the floor board of the car and consists of 70 the following parts:—A slotted rod 78, a lever 79, rod 80, bracket 81, spring 82, catch 83, foot piece 84, and floor board 85. The slot 87 in the rod 78 is so shaped as to allow the lever 79 ample play. The foot 75 valve 10 and the spring 12 perform an important part in the operation of my said brake. By pushing down slightly on the button 23 the port 31 is opened causing a partial vacuum to be drawn in the passage 28, pipe 27 and chamber 37—this partial vacuum being broken to a certain extent by air being sucked in through the valve 10 and entering the passage way 28 by vents 14. The farther the operator 80 pushes downwardly on the button 23 the farther down the piston 5 is carried—this causing spring 12 to give more tension to the valve 10 thereby allowing very little or no air to pass into the partial vacuum. In 85 this way you can cause the brake to be set "hard" or slightly. The rod 59 and its parts may be constructed so as to allow the free turning of the cross shaft 64 without carrying forwardly the piston 34 and its 90 parts. The said cross-shaft may be either the service or emergency brake cross-shaft and by the play of rod 59 and piston 61 in cylinder 58 the free movement of the hand brake or foot brake is allowed should it be 95 desired to use them. The rod 59 is fitted with a clevis on one end and a head as shown on the other end. The cap and guide 60 is threaded to the tube 58. The rod 92 is square so as not to allow the part 43 to 100 turn. The drop hanger 63 is split on the head so as to permit it to be attached to the cross rod without removing the same. The part 90 is a pull-back spring to be attached 105 to the brakes on the car. 110

I claim:—

1. In a brake the combination with a manifold of a cylinder having side apertures and an upper and lower aperture; tubing connecting said manifold with said cylinder; a piston in said cylinder having a transverse passage therethrough and a bypass and having a piston-rod projecting through the upper end of said cylinder provided with a head; a spring on said piston-rod between said cylinder and said head; a steering-post having a longitudinal passage therethrough; a rod connected to said head and extending into said steering post; a joint connected to said rod in said steering post, and projecting through said steering-post and provided with a push-button; a cylinder having end openings; a pipe connecting said first-mentioned cylinder with said cylinder having end openings; a box 120

125

130

- projecting from said cylinder having end openings; a piston in said cylinder having end openings and having a piston-rod projecting from the same and through one of the end openings of said cylinder; a toothed-rod connected to said piston-rod last-mentioned and having an extension slidably projecting through said box; a piston-cylinder pivotally connected to said extension; 10 a piston having a rod projecting through the piston-cylinder last-mentioned; a pair of pivoted arms, one of said arms being connected to the rod last-mentioned and the other of said arms having a rod extending outwardly therefrom; a drum; a centrally pivoted band in said drum endwise provided with shoes; an arm pivoted to the rod last-mentioned and provided with a movable spreader between said shoes and engageable therewith; a vertically acting dog engageable with said toothed-bar and means in connection with said cylinder having said apertures and upper and lower apertures and said cylinder having end openings, and 15 including a piston connected to said dog and a piston-cylinder therefor, for actuating said dog.
2. In brake mechanism, in combination, a manifold, a cylinder, direct pipe connections between said manifold and said cylinder, a piston in said cylinder having apertures therethrough, a piston-cylinder having a pipe connection with said cylinder, a piston in said piston-cylinder having a piston-rod and toothed bar extending therefrom, means for setting and releasing brakes in connection with said bar, a piston carrying a dog engageable with the teeth of said bar, a casing having apertures containing the 20 piston carrying said dog and tubing connecting said cylinder with said casing and
- tubing connecting said piston-cylinder with said casing.
3. In brake mechanism, a slidably supported toothed bar, a dog engageable with the teeth of said bar, a vertically movable piece connected to said dog, a lever engaging said piece, a resiliently slideable rod engaging said lever and a foot piece for depressing said rod. 25
4. In brake mechanism in combination with a manifold a piston-cylinder having a pipe connection and having an open valve seat in its lower end and a transverse wall therein having openings, a piston in said cylinder having a transverse aperture therethrough, a resiliently movable rod in one of said openings said rod carrying a head engageable with said valve seat, and a piston-cylinder having a pipe connection with said cylinder. 30
5. In brake mechanism means for holding the brake in a set position including a casing, an end cylinder and a side cylinder secured to and opening into said casing; a toothed rod in said casing; a piston in said end cylinder connected to said toothed rod; a piston in said side cylinder having a dog extending into said casing and engageable with said toothed rod, and means for creating a partial vacuum in said cylinders for raising said dog and moving said toothed rod to release the brake, and for admitting air into said cylinders for moving said toothed rod in the opposite direction and lowering said dog for setting the brake. 35
